Fig.3

Fig.4

FIG. 1 is a top plan view of a roller drape anchor for prestressed concrete showing my new design,

FIG. 2 is a side elevational view thereof,

FIG. 3 is a side elevational view taken at a right angle to FIG. 2, and

FIG. 4 is a bottom plan view.

The dominant feature of the design resides in the full line portion of the drawing.

The remaining three pairs of rollers which would be apparent in FIGS. 2 and 3, similar to the one pair shown therein, have been omitted for convenience of illustration.

I claim:

The ornamental design for a roller drape anchor for prestressed concrete, as shown and described.
